UNITED STATES PATENT OFFICE.

CHARLES MINSHALL, OF TERRE HAUTE, INDIANA, ASSIGNOR TO STANDARD WHEEL COMPANY, OF SAME PLACE.

DESIGN FOR A HUB-FLANGE.

SPECIFICATION forming part of Design No. 34,289, dated March 26, 1901.

Application filed December 14, 1900. Serial No. 39,929. Term of patent 7 years.

To all whom it may concern:

Be it known that I, CHARLES MINSHALL, a citizen of the United States, residing at Terre Haute, in the county of Vigo and State of Indiana, have invented and produced a new and original Design for Hub-Flanges; and I do hereby declare the following to be a full, clear, and exact description of the invention, such as will enable others skilled in the art to which it appertains to make and use the same.

Figure 1 is a side elevation, and Fig. 2 an end view, of a hub-flange embodying my new design.

The large portion of the flange (shown at the left-hand end of Fig. 1 in dotted lines) is a minor portion of my new design, and its exact configuration is therefore of less importance than the portion shown in full lines, which constitutes the essential feature of my new

design and embraces the cylindrical portion A, provided with parallel rows of pyramidal projections a, rising above the adjacent portion of the flange. Outside of this portion A is a circumferential groove B, and beyond that a straight cylindrical smooth portion C of about the same diameter as the portion A at the bases of the projection a and having a square edge c.

Having thus described my invention, what I claim is—

The design for a hub-flange, substantially as herein shown and described.

In testimony whereof I affix my signature in presence of two witnesses.

CHARLES MINSHALL.

Witnesses:

HARRY A. WAY,
W. H. CROOK.
